UNITED STATES PATENT OFFICE

WILLIAM HIGGINS, OF CHICAGO, ILLINOIS

WINDOW VENTILATOR AND DUST ELIMINATOR

Application filed June 12, 1929. Serial No. 370,350.

This invention relates to an improved ventilator in the form of a window screen of the variety including an appropriately anchored spring roller on which cloth fabric is wound, and wherein the free end of the fabric is attached to a sliding window sash, whereby to cause the screen to operate simultaneously with the opening and closing of said sash.

The purpose of the invention is to generally improve upon screen constructions of this class by providing an arrangement which is dependable, efficient, economical, capable of inexpensive and expeditious installation and otherwise susceptible of fulfilling the requirements of a structure of this class for screening and ventilating purposes.

In the drawings:

Figure 1 is a fragmentary perspective view of a window equipped with a screen constructed in accordance with the present invention.

Figure 2 is a vertical sectional view through the same.

Figure 3 is a perspective view of a vertical guide channel.

Figure 4 is a fragmentary sectional view of a spring roller retaining and bearing cup.

Referring now to the drawings, in Figure 1 it will be seen that the reference character 5 designates generally a window frame and 6 represents the lower sliding sash. The reference character 7 designates the customary apron and 8 the window sill. In accordance with the present invention the lower frame 35 bar of the sash 6 is provided with attaching hooks 9 with which the screen is detachably connected. The screen is here shown in the form of a suitable cloth fabric and is generally designated by the reference character 40 10. One end is wound on a spring returned roller 11, and the opposite end is provided with a reinforcing rod or bar 12 which is engaged over the retaining hooks 9. This permits quick attachment and detachment. The 45 fixtures employed for mounting the screen on the window frame comprise a pair of roller cups each of which is designated by the reference character 13. Each cup includes an inwardly pressed portion 14 having an opening 50 for reception of the pintle 15 of the roller

as seen in Figure 4. Each cup also includes a substantially U-shaped upstanding guide 16 through which the screen or fabric slides. I have found it expedient to fasten the cup in place by using a pair of eye bolts. One eye bolt is designated by the reference character 17 in Figure 2 and is secured in the sill, and provides an anchor for the cup. The eye bolts 17 pass through slotted projections 17' on the cups 13. The cup in turn is formed with a horizontal slot 18, and the eye 19 of the remaining eye bolt cooperates with this slot and extends across the same as seen in Figure 2 to hold the cup in place. However, by turning the eye to align with the slot it is obvious that the cup may be properly removed.

Associated with the vertical edges of the screen and detachably mounted on the frame 5 are channel guides 20. The lower end of one flange of each guide is offset as at 21 and fixed telescopically over the U-shaped guide 16. The upper end of the web portion is formed with a vertical slot 21', with which an eye bolt or turn button 22 is connected as seen in Figure 2. This allows the guide to be removed whenever desired.

The reference character A designates generally a casing for the roller and screen. This casing is substantially semi-circular in cross sectional shape as seen in Figure 2 and embraces the roller and the screen which is wound thereon. It is made up of complementary sections 23 and 24, fitted telescopically together to permit adjustment in width and which are fitted telescopically into the cups 13 at the opposite ends of the structure. This casing is a protector and preserves the screen from deterioration, especially when it is completely wound up.

In practice, the roller cups are fastened on the sill at opposite sides of the frame and the pintles of the spring returned roller are journaled therein. Then the channel guides 20 are fitted telescopically in place and fastened. The rod equipped end of the screen is engaged over the hooks 9. The result is that as the sash 6 is raised or lowered, the screen will operate simultaneously therewith.

The simplicity of the construction is such

as to make it unnecessary to include a more detailed description. Minor changes in shape, size, materials and rearrangement of details may be resorted to in actual practice
5 if desired.

What is claimed is:

As a new article of manufacture, a window fixture for use in association with a roller screen of the class described comprising a
10 cup having a horizontally disposed, integral slotted projection on its lower side constituting means for securing said cup to a window sill, said cup being further provided with an apertured depressed central portion to
15 receive the pintle of the screen roller in a manner to support the same in the cup, an integral upstanding extension of substantially
20 U-shaped horizontal cross-section formed laterally on the cup at one side thereof and constituting a guide for the passage of the screen, and an elongated substantially
25 U-shaped vertically disposed guide bar secured, at its upper end, to the window frame and having its lower end portion telescopically and detachably mounted for support on the cup guide.

In testimony whereof, I affix my signature.

WILLIAM HIGGINS.
